UNITED STATES PATENT OFFICE.

JOHN J. HOFFMAN, OF NEW KENSINGTON, PENNSYLVANIA, ASSIGNOR, BY MESNE ASSIGNMENTS, TO P. H. MURPHY COMPANY, OF PARNASSUS, PENNSYLVANIA, A CORPORATION OF PENNSYLVANIA.

CAR-ROOF.

1,092,485.

Specification of Letters Patent.

Patented Apr. 7, 1914.

Application filed May 15, 1912. Serial No. 697,405.

To all whom it may concern:

Be it known that I, JOHN J. HOFFMAN, a citizen of the United States, and a resident of the city of New Kensington, in the county of Westmoreland and State of Pennsylvania, have invented a new and useful Improvement in Car-Roofs, of which the following is a specification.

My invention relates to outside metal roofs for freight cars of the type known as radial roofs, and resides in an improved form of cover strip for the joints between the metal roof sheets of which the roof covering is composed, and in improved means 15 for securing the roof covering upon the roof substructure or framing of the car.

The object of my invention is to reduce the number of different parts required to form a complete roof covering, and to secure the roof covering to the roof substructure in such manner that the sagging, racking, and twisting of the car body in service shall not result in straining, tearing, or buckling the roof covering.

Another object of my invention is the removal of clips or other fastening means for securing the roof covering along the eaves of the car to a place less exposed to injury, and the elimination of bolt holes through the 25 fascia board and car siding at the eaves through which water may find its way into the car.

Further objects of my invention will appear in connection with the description of the embodiment thereof illustrated in the accompanying drawings, and the novel features of my invention will be more particularly pointed out in the appended claims.

In the drawings, in which like characters wherever they appear throughout the several views are used to designate like parts, Figure 1 is a top plan view of a portion of a car roof embodying my invention, with 40 the roof covering partly removed to show the car framing beneath; Fig. 2 is a vertical transverse section through the same on the line 2—2 in Fig. 1, showing a seam cover and carline in side elevation; Fig. 3 is an enlarged view in side elevation of a portion thereof at the eaves, showing the shape of the side flanges of the roof sheets and relative position of the same cover with 45 respect thereto in dotted lines; Fig. 4 is 50 a vertical transverse section through the eaves of the car on the line 4—4 in Fig. 1,

showing the end portion of a carline in side elevation; Fig. 5 is a vertical longitudinal section through the car roof at the eaves on the line 5—5 in Fig. 1, showing a fastening bolt for a seam cover in elevation; Fig. 6 is a perspective view of the end portion of a seam cover; Fig. 7 is a plan view of the end of the sheet metal strip or blank from which the seam cover shown in Fig. 6 is formed, the dotted lines indicating the lines upon which it is bent or folded in the forming operation; Fig. 8 is a perspective view of a clamping washer for securing the seam cover in position; and Fig. 9 is a perspective view of a combined bolt lock and seam cover saddle forming a part of my invention.

In the drawings I have illustrated my invention embodied in a metal roof for a box car having wood side and end plates 11, 12 and side and end sheathing 13, 14, but its use is not restricted to cars having wood bodies. Referring to the drawings, metal carlines 15, T-shaped in cross section, are arranged at spaced intervals lengthwise of the car to extend across the car from side plate to side plate, the ends of the carlines being turned down outside the side plate and securely bolted thereto. Purlins 16 extending lengthwise of the car and arranged parallel to each other at spaced intervals crosswise of the car are securely bolted to the carlines and to the end plates, forming with the carlines and side and end plates a rigid framework for supporting the roof covering. Filler strips 17 are nailed upon the tops of the purlins to support the roof sheets. In the form of construction shown in the drawings, the carlines are bent in arcs of circles and arranged with their base flanges 18 resting on the side plates and their middle flanges or webs 19 extending upwardly, in parallel vertical curves, and the purlins are secured to the under sides thereof of forming a rigid upwardly arched framework. Roof sheets 20, formed of heavy galvanized iron or other suitable material and having their side margins flanged up and rebent inwardly to form hooked flanges 21, are arranged upon the filler strips 17 to extend from eaves to eaves of the car, and with their ends 22 turned down into rabbets 23 in the fascia boards 24 secured on the outside of the side sheathing of the car at the eaves. The thickness of the filler strips 17 is less than the height of the vertical webs

19 of the carlines so that these webs stick up between the side flanges 21 of the roof sheets and prevent movement of the latter lengthwise of the car. The width of the roof sheets is slightly less than the distance between adjacent carline webs so that slight movement of the roof sheets lengthwise of the car is permitted. The width and depth of the rabbet 23 in the fascia boards 24 are slightly greater than necessary to accommodate the turned down ends 22 of the roof sheets, thereby permitting slight movement of the roof sheets crosswise of the car.

Seam covers 25 of inverted channel shape and having lateral flanges 26 extending outwardly from the lower edge of each side wall, are arranged upon the roof sheets at the joints between adjacent sheets to cover their upstanding side flanges and the webs of the carlines. The space within the seam cover is slightly wider than the overall distance from the inside extremity of the upstanding flange of one sheet to the inside extremity of the upstanding flange of the adjacent sheet, so that the roof sheets are allowed some sidewise motion before their flanges come in contact with the inside of the seam cap. The side walls of the seam caps are flared toward the lower edges where they meet the lateral flanges 26, thus providing an enlarged space 27 between the side flanges of the roof sheets and the side walls of the seam covers. This space curves as a gutter to conduct water and dirt along the margins of the roof sheets and off the eaves. The tops of the seam covers extend over the tops of the inwardly and downwardly rebent margins of the roof sheet flanges at a distance above them, thus leaving a considerable space over the inturned margins of the roof sheet side flanges within the seam covers. Any water which may splash into this space will run off the slightly downwardly inclined inturned margins of the roof sheet side flanges, and down the inside walls of the seam covers and so off the eaves of the car. The ends of the seam covers are bent down over the eaves of the car, the downturned end portions 28 serving to close the ends of the channel spaces beneath the seam covers and prevent water from entering these spaces and finding its way inside of the car. In order to form the folded end as shown in Fig. 6 of the drawings, the lateral flanges 26 are notched or cut away at the end of the sheet metal strip or blank from which the seam cap is formed, as shown in Fig. 7 of the drawings, and the narrow end portion of the blank is first flattened out and then folded up at the edges and bent down tight across the end of the channel, the dotted lines in Fig. 7 indicating the lines of fold. At the same time that the end portions are flattened out, they are crimped longitudinally. The crimped

middle part of the downturned end of the seam cap is bent in, forming an inwardly projecting lug 30 which projects into the rabbet in the upper corner of the fascia between the downturned ends 22 of the roof sheets. The lower edges of the ends 28 of the seam covers lie outside the downturned corners of the adjacent roof sheets and limit the outward sliding movement of the sheets at the eaves.

The seam covers are rigidly secured to the vertical webs 19 of the carlines by means of bolts 31 inserted in T slots 32 formed in the top edges of the carline webs. The bolts are held in position in the slots by locking pieces 33 provided with perforations 39 shaped to embrace the shank of the bolt. The locking piece is slipped down over the bolt and seated on the top of the carline web, being provided with ribs 34 on its under side to embrace the edge of the web. The locking pieces 33 also serve as saddles for supporting the seam covers, and are shaped on their upper sides to fit the inside of the latter. The seam covers are perforated to receive the bolts and are slipped down over the saddles and secured thereto by washers 37 and nuts 38 on the bolts. The seam covers are formed with upturned flanges 35 surrounding the bolt holes, and the washers 37 have their under sides shaped to fit the top of the seam cover and provided with recesses to receive gaskets 36 slipped over the bolts and clamped in place on top of the seam cover bolt hole flanges, thus insuring that no water shall find its way through the bolt holes. After the nuts are tightened up the ends of the bolts are riveted over to secure the parts from working loose. At the ridge of the car the washers 37 are omitted and wood running board saddles 40 are bolted down upon the tops of the seam covers, the bolt hole flanges digging into the wood and forming a water tight joint therewith. The running boards 41 may be secured to the running board saddles by nails or other convenient means. If it is desired to use metal running board saddles the ends thereof may be formed on the under side to receive the seam covers and gaskets in a manner similar to the washers 37 and fastened by nuts in the same way.

Having described one embodiment of my invention, I do not wish to be limited to the precise form thereof shown, but

What I claim and desire to secure by Letters Patent is as follows:

1. A seam cover of trough shape formed from a strip of sheet metal, the ends thereof being crimped longitudinally and flattened out and bent into planes transverse to the longitudinal axis of the seam cover, thereby forming closures for the ends of the trough.

2. A seam cover of trough shape formed

from sheet metal, said seam cover having its ends crimped longitudinally and bent into planes transverse to the longitudinal axis thereof, thereby forming closures for the ends of the trough.

3. In a car roof comprising metal roof sheets separated by joints transverse to the eaves of the car, seam covers of inverted trough shape for said joints arranged to rest 10 on the margins of the roof sheets adjacent said joints, said seam covers each being formed from a strip of sheet metal, the eaves ends thereof being crimped longitudinally, said crimped portions being bent down over 15 the ends of said joints, thereby forming eaves covers therefor.

4. In a car roof comprising metal roof sheets separated by joints transverse to the eaves of the car, seam covers of inverted 20 trough shape for said joints arranged to rest on the margins of the roof sheets adjacent said joints, said seam covers being formed from sheet metal and the eaves ends thereof being folded up and bent down in planes 25 transverse to the longitudinal axis of the seam cover, and vertical inward crimps extending upwardly from the lower margins of said downwardly bent ends.

5. In a car roof comprising metal roof 30 sheets separated by joints transverse to the eaves of the car, seam covers of inverted trough shape covering said joints with their ends overhanging the eaves, said seam covers having lateral flanges along the lower 35 edges of their side walls arranged to rest on the margins of the roof sheets adjacent said joints, said seam covers each being formed from a strip of sheet metal, the overhanging eaves ends thereof being narrower than the 40 flanged middle portions and crimped longitudinally, said overhanging portions being bent down in planes transverse to the longitudinal axis of the seam cover to cover the ends of said joints.

45 6. In a car roof comprising spaced roof sheets loosely secured thereon having end flanges turned down at the eaves, cover strips lapping the margins of adjacent roof sheets, said cover strips having their ends turned 50 down over the end flanges of said roof sheets

and spaced therefrom, and inward projections on the downturned ends of said cover strips, said projections extending between the downturned flanges of said roof sheets.

7. In a car roof comprising spaced roof 55 sheets loosely secured thereon having up-standing side flanges and end flanges turned down at the eaves, inverted channel cover strips lapping the margins of adjacent roof sheets and inclosing said side flanges, said 60 cover strips having their ends flattened at the edges and turned down over the end flanges of said roof sheets, and inward projections extending between the downturned flanges of said roof sheets.

8. In a car roof comprising side plates and carlines, spaced roof sheets extending from side plate to side plate and movably arranged with respect thereto, said roof sheets having downturned end flanges overhanging 70 the side plates and spaced therefrom, and securing means for said roof sheets comprising cover strips lapping the margins of adjacent roof sheets and free from the side plates, said cover strips being rigidly secured to the carlines and having downturned ends overlapping the corners of the downturned end flanges on said roof sheets.

9. In a car roof comprising side plates and carlines, spaced roof sheets extending 80 from side plate to side plate and movably arranged with respect thereto, said roof sheets having downturned end flanges overhanging the side plates, and securing means for said roof sheets comprising cover strips lapping 85 the margins of adjacent roof sheets and rigidly secured to the carlines, said cover strips being free from the side plates and terminating in depending portions overhanging the side plates and spaced therefrom, said depending portions overlapping 90 the corners of the downturned end flanges on said roof sheets.

Signed at New Kensington, Pennsylvania,
this 10th day of May, 1912.

JOHN J. HOFFMAN.
